UNITED STATES PATENT OFFICE.

MAX MUELLER, OF ST. LOUIS, MISSOURI.

TILE-CUTTING TABLE.

1,004,062.

Specification of Letters Patent. Patented Sept. 26, 1911.

Application filed June 8, 1910. Serial No. 565,822.

To all whom it may concern:

Be it known that I, MAX MUELLER, a subject of the Emperor of Germany, and resident of St. Louis, Missouri, have invented 5 certain new and useful Improvements in Tile-Cutting Tables, of which the following is a specification containing a full, clear, and exact description, reference being had to the accompanying drawings, forming a part 10 hereof.

My invention relates to improvements in tile cutting tables, the object of my invention being to construct a tile cutting machine in which the operation of cutting the 15 tile is continuous, that is can be accomplished without stopping the tile forming machine.

A further object of my invention is to 20 construct a machine for continuously cutting tile and the like without the employment of an extraneous driving mechanism, the cutting members being driven solely by the weight and pressure of the tile from the tile forming machine.

25 For the above purposes my invention consists in certain novel features of construction and arrangement of parts as will be hereinafter more fully described, pointed out in the claims and illustrated by the accompanying drawings, in which:

Figure 1 is an elevation of the complete tile cutting machine, a portion of the tile forming machine and the product therefrom being shown in dotted lines; Fig. 2 is 35 a plan of the complete tile cutting machine; Fig. 3 is a transverse, sectional elevation of the machine taken on the line 3—3 of Fig. 1; Fig. 4 is a view illustrating the cutting member in a position after a cut has been 40 made; Fig. 5 is an enlarged, detail elevation of the cutting frame support taken approximately on the line 5—5 of Fig. 3; Fig. 6 is a sectional elevation taken on the line 6—6 of Fig. 5; Fig. 7 is a sectional elevation 45 illustrating the cams for operating the cutting members taken on the line 7—7 of Fig. 3; Fig. 8 is an enlarged, detail, sectional elevation illustrating the means whereby the cutting members are caused to move with 50 the tile during the time a cut is being made, taken on the line 8—8 of Fig. 2; Fig. 9 is an enlarged elevation partly in section 55 illustrating the cam which disconnects the cutting members from the conveyer after a cut has been made; and Fig. 10 is a detail,

right hand elevation illustrating a portion of the means for returning the cutting members to their initial positions.

Referring by numerals to the accompanying drawings: 1—1 designate the end frame members which are connected by the track ways 2, the track ways being preferably constructed of angle iron having horizontal portions between the frame members 1 which are connected with the rounded end 60 portions 3, the portions 2 and 3 forming a continuous track way. Arranged beneath the lowermost track way 2 is a track way 4. Arranged for travel on the track way is an 65 endless conveyer which is composed of the links 5, each end of each link terminating in a down-turned perforated extension 6.

7 designates shafts which are extended through the extensions 6 of the links for 70 pivotally connecting the links in pairs and 75 for the support of the rollers 8, which rollers are designed for travel upon the track ways. Between each pair of links is a tile carrying block 9 the upper face of each of which is shaped to conform with the articles 80 to be cut, as shown, the blocks each are provided with trough-shaped depressions 10. This form of conveyer block is designed for 85 use in the formation of hollow drain tile as indicated by dotted lines in Figs. 1, 3 and 4. 85 As shown, each of the blocks is of a length slightly less than the length of the links so that there will be a space between each pair of blocks for the operation of the tile cutting device.

90 11 designates a shaft which is loosely mounted on the left hand side of the machine in bearings formed adjacent the tops of the frame members 1. Carried by the shaft 11 are the cross-fittings 12 secured to 95 move with the shaft by the set screws 13. Carried by each cross-fitting is a bow-shaped frame 14, the frames being connected by the cross-rods 15. At the outer free end of each frame there is an eye 16 and secured to each 100 of the eyes 16 there is a wire 17. In the frame members diametrically opposite the eyes 16 are the bolts 18 having hooks at their inner ends to which the wires 17 are secured. The opposite or outer ends of 105 the bolts 18 are threaded to receive the winged nuts 19. Arranged adjacent the bolts 18 are the projections 20 arranged to engage with the wires 17 for the purpose of adding tension to the wires and to prevent to 110

a degree the turning of the bolts 18. The arm of one of the cross-fittings opposed to the arm carrying the frame 14 carries a finger 21 the projecting portion of which is angular. Carried by the finger 21 is a set screw 22 arranged for operation in the slot 23 formed in the arm of the cross-fittings, the slot and set screw acting to limit the movements of the finger 21 in a rotary direction.

24 designates a spring which embraces the fitting having its one end secured to the fitting and its opposite end secured to the set screw.

25 designates a semicylindrical, metallic casing supported beneath the shaft 11 upon the uprights 26 and is secured to the track way 2 by means of the bolts 27. Secured on the inside face of the casing 25 are the curved ribs 28 forming a cam way 29 through which the finger 21 travels for raising and lowering the frames 14. For causing the frames 14 to move lengthwise of the machine in one direction there is arranged on each alternate link of the conveyer a member 30 projecting laterally, which are arranged to engage with a lever 31 carried by the shaft 11 and secured thereto against longitudinal movement by means of the collars 32. The lever 31 is provided with an integral extension 33 arranged for engagement with the outer end of the casing 25 as required to hold the lever in a position engaging with the projection 30. For moving the frames rearwardly or to their initial positions I have provided the pitman 34 which is connected with the lever 31 at one end and at its opposite end with the lever 35, which lever is pivoted to the track way 4. Connected with the lever 35 is a link 36, the forward end of which carries a down-turned projection 37 extended laterally from which is a roller 38 arranged for travel in a guide 39 which is secured to the track way 2, the projection 37 being arranged for engagement with the projections 30. The guide way 39 is so shaped as to elevate the projection 37 out of the path of travel of the projections 30 at times. For carrying the frames 14 in a nonoperative or elevated position, or in other words, to support them while they are returning to their initial positions, I have provided the arm 40 which is carried by one of the frames in a position adjacent the cross-coupling 12, the free end of which arm 40 terminates in a shoe 41 designed for travel upon the resilient track 42 lying adjacent the left hand margin of the casing 25 and being fixed at its forward end to the casing, and, adjacent its free end there is an up-turned, curved portion 43 against which the shoe 41 engages to start the frames to fall into an operative position. At the forward end of the track and secured to the casing 25 is

the cam groove 44 which engages the shoe 41 to lift the frames 14 to an inoperative position.

In the practical operation of the machine assuming the parts to be in position as shown in Figs. 1 and 3, it is obvious that as the tiling or product of the tile forming machine as it is forced from the tile forming machine will be supplied to the conveyer blocks 9, and as the tile is forced from the machine by its weight and engagement with the conveyer blocks the entire conveyer is moved without extraneous power. By reason of the engagement of the projections 30, carried by the links of the conveyer, with the lever 31 the frames 14 will be moved lengthwise of the machine and at the same rate of speed as the travel of the conveyer. Simultaneously with the moving of the frames 14 lengthwise relative the machine they are brought to a cutting position by means of the finger 21 engaging in the cam groove 29 which, as shown in Fig. 7, is inclined downwardly for a portion of its length and thence upwardly, the downwardly inclined portion serving to move, gradually, the frames 14 and the wires, which perform the cutting, downwardly through the tile, the upwardly inclined portion serving to lift the frames and the cutting wires out of the tile, all of which is accomplished while the tile is moving.

As shown in the drawings, the conveyer blocks are provided with two depressions each and there is provided a pair of frames 14 having cutting wires. By such a machine two tiles may be cut in sections at the same time, this being my preferred form of machine. If only a single tile is to be cut the conveyer blocks are provided with a face to receive one tile only and one of the frames and cutting wires is dispensed with.

After the machine has reached the limit of its cutting movement one of the projections 30 engages the down-turned extension 37 of the link 36 and moves the entire link rearwardly. In moving the link 36 rearwardly through the medium of the lever 35 and pitman 34, the lever 31 together with the shaft 11 and frames 14 are moved to their initial or starting positions. Just prior to the full limit of movement rearwardly the shoe 41 engages the curved portion 43 of the track 42 and causes the frames to fall to a cutting position.

The operation of depressing the wires through the tile, the advancing of the wires to move with the tile at the same time they are being forced through to cut the tile, the return of the frames and wires to their initial cutting positions is all carried on while the tile is being continuously formed and discharged from the tile forming machine.

I claim:

1. In a tile cutting table, a frame, end-

less track ways supported by the frame, an endless conveyer arranged for travel on the track ways, conveyer blocks spaced apart and carried by said conveyer, a shaft carried by the frame lengthwise thereof, a bow-shaped frame carried by said shaft, a cutting member carried by said bow-shaped frame, projections arranged at intervals on said conveyer, a lever secured to said shaft arranged for engagement with one of said projections so that as the conveyer is moved the shaft and said bow-shaped frame will move with the conveyer, a finger projecting downwardly from said bow-shaped frame, 15 a fixed cam groove for engagement with said finger for moving the bow-shaped frame so that the cutting member will be forced through the tile, said groove having an upwardly inclined portion for elevating 20 the cutting member from the tile and means operated by the conveyer for moving the bow-shaped frame and cutting member to its initial cutting position.

2. In a tile cutting table, a frame, endless track ways supported in the frame, an end- 25 less conveyer arranged for movement on said track ways, conveyer blocks spaced apart and carried by said conveyer, the upper faces of which are shaped to conform 30 with the tile to be cut, a shaft loosely supported in said frame lengthwise thereof, a number of bow-shaped frames interconnected and supported by said shaft, means whereby said frames are caused to move 35 lengthwise of the machine by said conveyer, a finger carried by one of said frames, a cam groove through which said finger travels to cause the frames to be brought to cutting positions and to elevate

the frames to non-cutting positions and 40 means operable by the conveyer for returning all of the parts to their initial cutting positions, said conveyer arranged to be moved solely by the engagement therewith of the tile discharged from a tile forming 45 machine.

3. In a tile cutting table, a frame, continuous track ways supported in the frame, an endless conveyer arranged for travel on the track ways, tile carrying blocks spaced 50 apart and carried by said conveyer, a shaft supported lengthwise of the table, bow-shaped frames supported by said shaft, cutting members carried by the bow-shaped frames, projections extending laterally from 55 the conveyer, a lever supported by said shaft arranged to engage with said projections for moving the shaft and the bow-shaped frames with the conveyer, a projection carried by one of said bow-shaped frames, a 60 cam having a downwardly inclined portion and an upwardly inclined portion to be engaged by said projection for moving the bow-shaped frames in positions whereby the cutting members are caused to pass down- 65 wardly and thence upwardly through the tile and means connected with said lever and operated by said projections on the conveyer for returning the cutting members to 70 their initial positions.

In testimony whereof, I have signed my name to this specification, in presence of two subscribing witnesses.

MAX MUELLER.
